(57) **CLAIM**

The ornamental design for a roof sheathing connector, as shown and described.

DESCRIPTION

FIG. 1 is a perspective view of a roof sheathing connector, showing my new design.

FIG. 2 is a right side view of the roof sheathing connector of FIG. 1, and the left side view being a mirror image.

FIG. 3 is a top view of the roof sheathing connector of FIG. 1.

FIG. 4 is a bottom view of the roof sheathing connector of FIG. 1; and,

FIG. 5 is a front view of the roof sheathing connector of FIG. 1, and the rear view being a mirror image.

The broken lines shown in the drawings depict portions of the roof sheathing connector that form no part of the claimed design. The roof sheathing connector is shown with symbolic breaks in its length. The break lines and the appearance of any portion of the article between the break lines forms no part of the claimed design.
